Primary Examiner — Mark A Goodwin*Assistant Examiner* — Adam C Mager(74) *Attorney, Agent, or Firm* — SHUTTLEWORTH & INGERSOLL, PLC; Timothy J. Klima(57) **CLAIM**

The ornamental design for a vehicle wheel rim as shown and described.

DESCRIPTION

FIG. 1 is a front view of a vehicle wheel rim;

FIG. 2 is a rear view thereof;

FIG. 3 is a right side view thereof;

FIG. 4 is a left side view thereof;

FIG. 5 is a top side view thereof;

FIG. 6 is a bottom side view thereof;

FIG. 7 is a front right side perspective view thereof; and,

FIG. 8 is a rear right side perspective view thereof.

Any broken lines in the figures illustrate portions of the vehicle wheel rim that form no part of the claimed design.
